UNITED STATES PATENT OFFICE

X-RAY APPARATUS AND SUPPLY CABLE FOR SAME

Albert Bouwers, Eindhoven, Netherlands, assignor
to N. V. Philips' Gloeilampenfabrieken, Eind-
hoven, Netherlands

Application April 6, 1931; Serial No. 523,200
In the Netherlands April 30, 1930

5 Claims. (Cl. 250—34)

In my copending application, Serial No. 257-045, filed February 25, 1928, is described an X-ray installation in which a cooling medium is supplied to a discharge tube through one or more passages provided within a current supply cable.

The present invention has for its object to improve such an installation and it concerns such a construction of the devices connecting the cable to the tube that during operation the cooling medium remains electrostatically unloaded.

The cable may be provided with a flexible closed tubing, for example a rubber tube, which is located within the current conductor of the cable and which extends as far as into a conducting contact member which, during operation, is connected to the electrode to be cooled. For causing the circulation to take place entirely through a cable, the flexible tubing may consist of two rubber tubes located concentrically within one another and connected during operation to nipples of the supply and discharge passages of the electrode to be cooled.

The invention prevents an electrostatic field from having a harmful influence on the cooling medium flowing through the cable. Especially if the cooling medium consists of a liquid, an electrostatic load may give rise to unfavourable phenomena such as the formation of vapour and gas, due to which the reliability of service of the cable and the connecting devices decreases. Besides, a concentric supply and discharge of the cooling medium gives a favourable distribution of the electric field in the dielectric of the cable and, in addition, gives a suitable solution of the problem of making the connection with the body to be cooled.

In my above-mentioned prior application there is described a mode of construction with concentric arrangement of the supply and discharge conduits but in this construction the cooling medium flows back through a space surrounding the current conductor due to which in the cooling medium is set up an electric field with all the disadvantages thereof.

The invention will be more clearly understood by referring to the accompanying drawing in which Fig. 1 represents schematically the connection of an X-ray tube with a cooling liquid pump.

Figure 2 shows by way of example the manner in which the connection of the cable to the tube may be effected.

Referring to Fig. 1, a grounded envelope 1,

which entirely surrounds an X-ray tube, has secured to it two high tension cables 2 and 3. The cable 3 is connected to a cooling liquid pump 4 which is driven by an electro-motor 5 from which it is insulated in the known manner against high tensions. Via this pump the electric current is supplied to the tube by the cable 3, which at the same time serves for the supply and discharge of the liquid for cooling the anode of the tube.

In Fig. 2 only part of the glass wall 10 of the X-ray tube is shown. A re-entrant portion 11 thereof encloses a tubular body 12 to the end of which is secured the head of the anode of the tube, this head not being shown in the drawing. Within the tube 12 is arranged a pipe 13 through which the liquid for cooling the anode is supplied. This liquid can flow back through the space between the pipe 13 and the tube 12. To the tube 12 is secured a bushing 14 which has a resilient edge 15.

The electric current is supplied by a cable 17 the tubular conductor of which is denoted by 19. This conductor contains two rubber tubes 16 and 18 of which the latter is located within the former. The exterior tube 16 is secured at its end to a nipple 20 which is fixed in the bushing 14. The end of the rubber tube 16 which is slid on the nipple is located in the annular space between the nipple 20 and the part 15 which is urged by resiliency to the outside. Said part engages a contact sleeve 21 to which the conductor 19 of the cable is secured.

The contact sleeve 21 is secured to a connecting piece 22 of insulating material which is slid on the end of the cable 17 and which is preferably cemented thereto with the aid of a binder, such as shellac, so that there is no air between the cable and the conductor 19 protruding therefrom and the connecting piece 22.

The cable 17 is enclosed by a metal sheath which, through the intermediary of rings 23 and 24, is electrically connected with the aid of a coupling nut 25 to the metal envelope 26 which entirely surrounds the tube 10. The connecting piece 22 fits into a cavity of a block 27 of insulating material in which the contact piece 21 is fixed. This block closes the end of an insulating cylinder 28 within which the X-ray tube is located.

The rubber tube 18 is slid on a nipple at the end of the pipe 13, which is held in its proper place by means of a perforated disc 29.

The electric current supplied by the conductor 19, flows via 21, 14 and 12 to the anode of the

tube. This conducting path lies entirely outside the path traversed by the cooling medium, so that the latter is electrostatically screened by a conducting wall and is located in a fieldless space.

What I claim is:

1. In an X-ray installation, an X-ray tube having internal portions to be cooled by circulating liquid introduced from the exterior, a flexible hose for the supply of cooling liquid and a second flexible hose for conducting the liquid away from the tube, one of said hoses being located within the other, a high-tension electrical cable having a hollow conductor, the said hoses lying in said hollow conductor, and means electrically connecting said hollow conductor to the portions of the X-ray tube to be cooled, said means defining an electric shield for the cooling liquid.

2. In an X-ray installation, an X-ray tube having a member to be cooled by a liquid medium, said member having a metal tubular extension adapted to receive the cooling liquid, a flexible hose connected to said extension serving to supply the cooling liquid thereto, a high-tension electric cable for supplying current to the X-ray tube and having a hollow conductor, means connecting said cable to said tube comprising a hollow insulating body forming an end portion of the cable and another hollow insulating body connected to the X-ray tube, said insulating bodies having mutually engaging surfaces and forming with the hollow conductor of the cable a continuous passage in which said flexible hose is located, the metal tubular extension of the X-ray tube extending in the hollow insulating portion connected to the tube, a metal tubular portion extending in the hollow insulating portion carried by the cable, connected to the hollow conductor of the cable, said tubular extension and metal tubular portion ending in a set of hollow electrical contact bushings, one engaging the other and surrounding the end of said flexible hose.

3. In an electric installation, a metallic envelope, an electric discharge tube mounted therein and having a portion to be put under high potential with respect to the envelope and to be

the end of the cable is introduced, means securing the metal sleeve of the cable to the metal envelope of the tube and means electrically connecting the hollow conductor with the portion of the tube to be supplied with current, a flexible hose adapted to be a conduit for the cooling liquid located in the hollow conductor of said cable, and means connecting said hose to the portion of the tube to be cooled, said last-mentioned means being concentrically surrounded by the means for electrically connecting the conductor with the tube.

4. In an X-ray installation an X-ray tube having portions to be cooled by a liquid medium, a high-tension electric cable for supplying current to the X-ray tube and having a hollow conductor forming a conduit in said cable for said cooling medium, means for connecting the conductor and tube, said means comprising insulating parts and hollow conductive parts, the latter being enclosed by said insulating parts, said hollow conductive parts forming a passage registering with the said conduit and defining together with the said hollow conductor a continuous conductive sleeve to prevent electric fields from intercepting the liquid.

5. In an X-ray installation, an X-ray tube having portions to be cooled by a liquid medium, a high-tension electric cable having a hollow conductor, means for connecting the cable and the tube, said means comprising a hollow conductive portion, the passages formed by said hollow conductive portion and said hollow conductor being in line with each other, a flexible hose extending through said cable and engaging said conductive portion, the latter defining together with the said hollow conductor an electric shield extending over the flexible hose and preventing electric lines of force from penetrating into the latter.

ALBERT BOUWERS.
